UNITED STATES PATENT OFFICE.

LOUIS A. EDWINSON, OF TOPEKA, KANSAS.

RATCHET-WRENCH.

Specification of Letters Patent. Patented Sept. 20, 1921.

1,391,619.

Application filed May 28, 1921. Serial No. 473,519.

To all whom it may concern:

Be it known that I, LOUIS A. EDWINSON, a citizen of the United States, residing at Topeka, in the county of Shawnee and State of Kansas, have invented certain new and useful Improvements in Ratchet-Wrenches, of which the following is a specification.

This invention relates to ratchet wrenches and has special reference to a ratchet wrench designed to reach bolts and nuts in places inaccessible by an ordinary wrench.

One important object of the invention is to improve the general construction of wrenches of this character.

A second important object of the invention is to provide an improved arrangement of operating means for such wrenches.

In using a ratchet wrench having a spring pressed pawl it frequently happens that a nut or bolt is too loose to overcome the pressure of the spring on the pawl and permit backward movement of the pawl relative to the ratchet when the handle of the wrench is moved to obtain a fresh grip on the ratchet. Consequently the wrench will not operate effectively.

A third object of the present invention is to provide, in a ratchet wrench, supplemental ratchet means whereby the wrench may be effectively operated on a bolt or nut irrespective of its looseness.

With the above and other objects in view, the invention consists in general of certain novel details of construction and combinations of parts hereinafter fully described, illustrated in the accompanying drawings, and specifically claimed.

In the accompanying drawings, like characters of reference indicate like parts in the several views, and:

Figure 1 is a side elevation of a wrench constructed in accordance with this invention.

Fig. 2 is a plan thereof.

Fig. 3 is a section on the line 3-3 of Fig. 2.

Fig. 4 is a section on the line 4-4 of Fig. 3.

In the embodiment of the invention herein illustrated there is provided a body member 10 preferably in the form of a flat bar having a handle 11 formed on one end and having the other end 12 offset from the axis of the handle and provided with a bearing opening 13. Mounted on this body is Z-shaped member 14 having a bearing opening

15 formed therein in alignment with the opening 13, the end of this member containing the opening being spaced from the body end 12. Between these two ends is located 60 a main ratchet member 16 having a journal 17 mounted in the opening 13 and a journal 18 mounted in the opening 15. The journal 18 is prolonged beyond the bearing and carries on its end a wrench socket 19 which 65 is detachably mounted on the journal projection by means of a screw 20. Surrounding the ratchet 16 is a housing 21 having a substantially cylindrical body and mounted on the journal 17 to revolve freely thereon. 70 This housing has the end, through which the journal 18 projects, closed by a plate 22. Projecting from one side of the housing is a lug 23 having a radial opening 24 therethrough which has an enlarged portion 25 75 at its inner end. Through the opening 24 projects the stem 26 of a pawl which has a beveled head 27 engaging the ratchet 16, a spring 28 being located in the opening portion 25 between said head and the interior 80 end of this portion of said opening. Through the stem 26 extends a cross pin 29 and in the lug 23 are formed opposed notches 30 in which the cross pin normally sits. By means of this arrangement the 85 pawl may be turned to face in either direction with respect to the ratchet as it may be moved outward by grasping the stem 26 and may then be rotated 180 degrees. Moreover the pawl may be held out of engagement with the ratchet by moving it outward and rotating it one quarter turn so that the cross pin will engage the face of the lug and will not enter the notches.

Depending from the sides of the bar 10 95 is a pair of lugs 31 between which is an opening 32. Through this opening passes an operating lever 33 fulcrumed on a bolt 34 passing through said lugs. This lever is provided at one end with a handle 35 and 100 has connected to its other end one end of a link 36 which has its other end connected to a lug extension 37 on the housing 21. By oscillating this handle 35 the housing and the pawl are given an oscillatory motion 105 and, with the socket holding a comparatively tight bolt or nut, the ratchet will be given the usual intermittent rotary movement.

Additional means are employed to insure 110 proper motion to the ratchet in case of loose nuts or bolts. To this end there is mounted

on the journal 18 outside the member 14 a ratchet 38 and on the member 14 is pivoted a double pawl 39 having a finger controlled end 40. In operating the device on loose nuts the main pawl is withdrawn. Then, by oscillating the handle 11 and moving the supplemental pawl alternately into and out of engagement with its ratchet the nut may be tightened sufficiently to permit use of the main pawl and ratchet which are then brought into operative relation in the manner above set forth.

There has thus been provided a simple and efficient device of the kind described and for the purpose specified.

It is obvious that minor changes may be made in the form and construction of the invention without departing from the material principles thereof. It is not therefore desired to confine the invention to the exact form herein shown and described, but it is wished to include all such as properly come within the scope claimed.

Having thus described the invention, what is claimed as new, is:—

1. A ratchet wrench having a body provided at one end with a handle, a socket revolubly mounted at the other end of the body, an operating lever pivoted to the body, a main ratchet mechanism associated with the socket and operable by said lever, and an auxiliary ratchet mechanism also

associated with the socket and operable through oscillations of said handle.

2. A ratchet wrench having a body provided with a handle at one end, a socket revolubly mounted at the other end of the body, an operating lever pivoted to the body, a pair of independent ratchets connected to the socket in fixed relation thereto, a pawl operatively associated with one of said ratchets, an operative connection between said pawl and lever, and a second pawl pivotally supported from the body to oscillate therewith and having operative association with the second ratchet.

3. A ratchet wrench having a body provided at one end with a handle and having a fork forming member at its other end, a ratchet between the sides of the fork, journals extending from the ratchet and revolubly mounted in the sides of the fork, a housing revolubly surrounding the ratchet, a reversible pawl mounted in the housing, a lever pivotally mounted on the body, a link connecting the housing and lever, a second ratchet fixed on one of the journals, a double pawl pivoted to the fork forming member and operatively associated with the second ratchet, and a socket carried by one of said journals.

In testimony whereof I affix my signature.

LOUIS A. EDWINSON.
